UNITED STATES PATENT OFFICE.

JOSEPH J. RAFTER, OF HARTFORD, CONNECTICUT, ASSIGNOR OF ONE-HALF TO RIAL S. PECK, OF HARTFORD, CONNECTICUT.

INKING-ROLLER.

SPECIFICATION forming part of Letters Patent No. 741,275, dated October 13, 1903.

Application filed September 4, 1902. Serial No. 122,025. (No model.)

To all whom it may concern:

Be it known that I, JOSEPH J. RAFTER, a citizen of the United States, residing in Hartford, in the county of Hartford and State of Connecticut, have invented certain new and useful Improvements in Inking-Rollers, of which the following is a specification.

This invention relates to inking-rollers, and has for its object to provide an improved roller which may be removed from the spindle.

Another object of the invention is to provide means for mounting two or more rollers upon a spindle.

Another object of the invention is to provide interrupted rollers for multicolor printing.

Another object of the invention is to provide means whereby rollers may be cast separately from the spindle and mounted thereon at will.

Heretofore printing-rollers, which are generally made from some plastic material, have been cast upon the spindle, thus making it necessary for the printer to have several spindles and ship the spindles to the roller-maker to cast the rollers upon them. It has also been the practice in printing several colors to run the work through the presses for every color. My invention contemplates casting or otherwise forming the ink or color receiving and distributing rollers separate and apart from the spindles or journals in such manner that they may be readily mounted upon and removed from the spindle or other journals and in any length, whereby one or more rollers may be placed upon a spindle, the length of the rollers to be determined by requirements of practice.

In the drawings accompanying and forming part of this specification, Figure 1 shows a form of my invention wherein there are two equal-sized rollers mounted upon a spindle and spaced apart. Fig. 2 is a similar view showing rollers of dissimilar lengths and broadly spaced, certain portions in each instance being shown in central vertical section. Fig. 3 is a perspective view of the end of a roller removed, partly broken away to show the inner tube. Fig. 4 is a perspective

of a form of spacer, and Fig. 5 is a perspective of a spindle with the rollers removed.

The spindle (designated in a general way by A) in the present instance is shown as comprising a body portion or shaft 7, with journals 8 at each end, and the rollers or ink receiving and distributing bodies (designated in a general way by B) comprise a body portion 9, made of any suitable material for receiving and distributing ink or other material which it is desired to apply in a similar manner. The rollers are cast or formed separate and apart from the spindle and, if desired, may be made upon a tube or sleeve 10, which in the present instance is shown as having a working fit with the body portion of the spindle. For ordinary work a single roller occupying any desired amount of the spindle may be mounted thereon and held, if desired, in such a manner as to compel it to rotate with the spindle by any suitable means, (here shown as a pin 11, passing through the spindle, which pin may engage suitable notches or lugs in the tube) or if the rollers are cast without tubes notches or lugs may be provided in or upon the rollers themselves, and for the purpose of conveniently removing the rollers a cotter-pin 12 may be provided for engaging the other end of the roller. Any suitable key or fastening device found desirable in practice may be employed at the ends. In Fig. 1 two rollers are shown as mounted upon a spindle in the manner described, and between the rollers is a tube 13, so disposed relatively to the rollers that it will in the present instance engage the tubes 10 upon which the rollers are cast and space them apart. If it should be desired with the device made as shown in Fig. 1 to employ a roller equal to the length of both of the sections of roller, it will merely be necessary to draw the cotter-pin and remove the roller and spacer-tube and change the places of the tube and the roller, thus bringing the tube 13 next the cotter-pin and the ends of the rollers abutting. Thus a continuous roller will be had. In Fig. 2 the rollers are shown as of dissimilar lengths, which will be convenient in cases where it is desired to do printing in one color with a smaller amount of printing.

of a different color; but it will not be necessary to use rollers of the same length for each color. In this instance, however, the end pin is shown as pressing into the roller 5 to engage a notch in the tube, thus presenting a flush-ended roller.

It may be desired in practice to hold the rollers merely from a pin at one end, in which instance a lock should be had between the 10 rollers and the scraper. A convenient form for so doing is illustrated in Figs. 3 and 4. The tubes upon which the rollers are mounted or cast and also the spacing-tube may be made at their ends as illustrated at Fig. 4, 15 wherein the tube 13' is shown as having notches 14 at one end and lugs or projections 15 at the other end adapted to mate with similarly-formed tubes. Thus it will be seen that the notch of the roller may be caused to 20 engage a stationary pin, either a spacer or a roller, put on the spindle and caused to have its notches engage the lugs, and so on until the spindle is filled, a cotter-pin engaging the lugs or projections upon the last roller.

25 Although the rollers have been shown as formed upon tubes and these mounted upon a spindle, yet it will be apparent that many other forms of construction may be adapted to produce the same result without departing 30 from my invention, and other devices may also be employed for holding the rollers stationary upon the spindle.

Having thus described my invention, what I claim, and desire to secure by Letters Patent, is—

35 1. The combination with a spindle provided with a pin at one end; a roller cast upon a tube having a working fit with the

spindle; notches in the end of the tube to engage the pin; lugs protruding from the opposite end of the tube; a spacer provided with similar notches and lugs; a roller similar to the first mounted upon the spindle and engaging the lugs of the spacer; and a cotter-pin engaging the lugs of the second roller. 40 45

2. The combination with a plurality of hollow cores, of a plurality of plastic rolls each cast upon one of the cores; a spindle with which the cores have a working fit and upon which they are mounted; an interchangeable 50 collar having a working fit with the spindle and mounted thereon between the cores; the ends of the collar abutting the adjacent ends of the cores to space the rolls; and mating locking-spaces upon the abutting ends of the 55 cores and collar respectively for preventing independent angular movement of the cores and collar upon the spindle.

3. In a printing-roll, the combination with a spindle providing journals, of a plurality of 60 interchangeable plastic rolls mounted thereon; hollow cores having a working fit with the spindle and upon which the rolls are cast; an interchangeable collar having a working fit with the spindle and mounted thereon between the rolls; mating notches and lugs carried by the abutting ends of the cores and collar and organized to lock the same from 65 independent angular movement upon the spindle; and means for locking the cores to 70 the spindle.

JOSEPH J. RAFTER.
